UNITED STATES PATENT OFFICE

162,394

POWER KNIFE SHARPENER

George T. Estfan, Wichita, Kans.

Application October 17, 1949, Serial No. 5,543

Term of patent 14 years

(Cl. D37—1)

To all whom it may concern:

Be it known that I, George T. Estfan, a citizen of the United States, residing at Wichita, State of Kansas, have invented a new, original, and ornamental Design for a Power Knife Sharpener, of which the following is a specification, reference being had to the accompanying drawing, forming a part hereof.

Fig. 1 is a top plan view of a knife sharpener embodying my new design;

Fig. 2 is a side view of the sharpener shown in Fig. 1;

Fig. 3 is an end view of the sharpener, both ends being identical in appearance; and

Fig. 4 is a perspective view showing that side of the machine opposite the one shown in Fig. 2.

I claim:

The ornamental design for a power knife sharpener, as shown.

GEORGE T. ESTFAN.
